UNITED STATES PATENT OFFICE.

JAY BRIGGS, OF HOOPESTON, ILLINOIS.

AUTOMATIC ELECTRIC CROSSING-GATE.

1,199,342.

Specification of Letters Patent. Patented Sept. 26, 1916.

Application filed December 19, 1914. Serial No. 878,060.

To all whom it may concern:

Be it known that I, JAY BRIGGS, a citizen of the United States, residing at Hoopeston, in the county of Vermilion and State of Illinois, have invented a new and useful 5 Automatic Electric Crossing-Gate, of which the following is a specification.

This invention relates to automatic electric crossing gates of the type disclosed in 10 my Patent No. 1,134,584, dated April 6, 1915, and the main object of the present invention is to provide electric controlling means for such gate which will not interfere with the usual operation of the ordinary 15 block signal system. The controlling apparatus for the type of gate disclosed in my said patent requires track sections at each side of the crossing which are open-circuited and are closed by the passage of the train 20 thereonto. In block systems in general use the track sections are normally on closed circuit and in order to adapt my invention for use in connection with a track protected by block signals I provide means hereinafter 25 set forth for normally putting the track sections adjacent to the crossing on closed circuit and for interrupting such closed circuit connection only during the time that the train is in position to control the gate, 30 thereby enabling the gate apparatus to operate in the required manner without interfering with the proper operation of the block signal system.

The accompanying drawings illustrate an 35 embodiment of my invention, and referring thereto Figure 1 is an elevation of the switch board apparatus for controlling the gate motor, said motor and a portion of the track adjacent to the crossing being shown 40 connected to said switch board; Fig. 2 is a vertical section of the gate means taken transversely of the track; Fig. 3 is a vertical section on line x^3-x^3 of Fig. 2; Fig. 4 is a diagram of the circuit connections for the 45 track sections controlling the gate, the parts being shown in the position occupied when the first wheels of the train are entering the gate controlling section; Fig. 5 is a vertical sectional view of one of the track 50 switches shown in Fig. 4; Fig. 6 is a view similar to Fig. 4, the parts being shown in position occupied when the last wheels of the train are entering the crossing section.

The switch board and gate apparatus are 55 substantially as shown in my previous patent, but in order to properly explain the op-

eration of my improved system controlling the same, such apparatus may be described as follows:

The gate apparatus is located at the crossing 1 where it traverses the track rails 2 and comprises, for example, in case of a single track, two gate arms 5 and 5', mounted at opposite sides of the track. A motor 10 is connected to operate the gate 60 arm 5 at one side of the track through gearing indicated at 9, and a drive connection 102 is provided from such gearing to the gate arm 5' at the other side of the track, so that said arms 5 and 5' operate in unison. 70

The motor 10 is controlled from the switch board indicated at 3, said switch board being provided with an armature switch 4 for controlling current through the armature of the motor to drive the motor in one or the 75 other direction, and a main switch 6 for controlling the circuit to start the motor when a train enters a gate-controlling section. The main switch lever 6 is operated in reverse directions by two solenoids 11 and 12 80 and is normally held in neutral or intermediate position by springs 13 operating on collars 14 on bar 15, said bar sliding in guides 16 and said collars engaging an arm 17 connected to the switch lever 6. Switch 85 lever 6 is also provided with an arm 18 having a contact segment 19 normally bridging two fixed contacts 20 and 21. Switch lever 6 carries at opposite sides of its pivot, main switch contacts 22 and 23 which normally 90 engage respectively with pairs of fixed contacts 24, 25 and 24', 25'. Above these pairs of contacts but normally out of contact with the switch contacts 22 are pairs of contacts 26, 27 and 26', 27'. Means are provided for 95 locking the main switch lever temporarily when it is operated in either direction, said means consisting, for example, of shoulders 100 30 on the bar 15 aforesaid adapted to be engaged by locking bars formed as, or connected to, cores 31 and 31' for locking solenoids 32, 32'. Said cores 31 and 31' carry, respectively, switch bars 34, 34' adapted to normally bridge the respective pairs of contacts 35, 36 and 35', 36'. The switch bars 34 and 105 34' carry a latch 37, 37' adapted to engage and operate a trip switch 38 or 38' which are normally held in contact with fixed contacts 39 and 39', for example, by springs 40. The armature reversing switch 4 is adapted to 110 bridge the respective pairs of contacts 41, 41' and 42, 42' being for example held in con-

tact with contacts 41 and 41' by gravity and drawn into contact with contacts 42 and 42' by the operation of the core 43 of a solenoid 44.

5 Switch means is provided for reversing the connections of the motor after the gate has been operated so that on further energization of the motor the gate will be restored to normal position. Said switch means may 10 consist of a contact 50 carried by a rod 51 which is moved in one direction or the other by arms 52 and 52' adapted to be engaged by a pin 53 connected to the gate carrying member 9, said contact 50 being adapted to 15 engage a pair of fixed contacts 51' when moved in one direction, and a pair of fixed contacts 52' when moved in the opposite direction.

20 The complete system of track section connections is shown in Fig. 4. Adjacent to the crossing 1 one of the track rails, indicated at 7, may be formed as an electrically continuous rail extending for the whole length of the block indicated at B, the adjacent blocks A and C being insulated therefrom. 25 The other rail of the track may be divided into two sections 8 and 8' at opposite sides of the crossing and short reversing sections 8^a and 8^b between the respective sections 8 and 8' and the corresponding rail of the next block. Switches 12, 12' and 12'' operated by solenoids 54, 54^a and 54^b are provided adjacent to the breaks between the respective sections 8^a, 8, 8' and 8^b, said switches being 30 normally closed so that all said sections constitute normally a continuous rail section adapted for operation in the usual manner of the ordinary block system.

35 55 indicates the track battery for the block 40 system having opposite sides connected to the respective sides or rails of the track of block B, and 56 indicates the block signal relay connected across the track so as to be normally energized by said track battery by 45 current passing through the normally continuous rail sections of block B.

Near the outer end of the track sections 8 and 8' are provided track switches 58 and 58' which may be of any suitable type, for 50 example as shown in Fig. 5, consisting of levers normally pressed away from the contact 59 by the spring 60 and pressed onto said contact by engagement therewith of the wheels of the train. These switches 58 are of the usual stick switch type, shown in 55 Fig. 5, provided with electromagnetic means for holding the switch closed when it is moved to closed position by operation of a train wheel, the switch being retained in that 60 position until the circuit is broken at the trip switch 38 or 38' of the gate operating means. One side of each of said track switches is connected by wires 61 and 61' respectively to a wire 62 which extends substantially the length of the sections 8 and 8'

and is connected to one side of magnet 54. The other side of the magnet or solenoid 54 is connected by wire 63 to magnet or solenoid 54^a controlling the magnetic break switch for the middle break between the sections 8 and 8'. From said solenoid 54^a a wire 64 leads to a magnet 65 whence a wire 66 leads to wires 67, 67' connected to one side of low voltage batteries 68, 68'. Batteries 68 and 68' are connected at their other sides respectively to wires 70 and 70' both leading to a wire 70^a connected to trip switch 38. A wire 71 connects the contacts 39, 39' of the two trip switches and a wire 72 leads from the trip switch 38' to solenoid 54^b. From the other side of said solenoid 54^b a wire 73 leads to wires 74, 74' connected to the other side of the track switches 58', 58 aforesaid so that on closure of either of said track switches a circuit will be established from the batteries 68 and 68' through the several solenoids 54, 54^a and 54^b in series relation, this circuit also including the magnet 65 and the trip levers 38 and 38'.

70 The magnet 65 is for the purpose of putting the controlling circuits for the switch board 3 in operative connection with the track sections 8 and 8' when the circuit through said magnet is energized by closure of one of the track switches 58, 58'. The armature 76 for said magnet co-operates with four contacts 77, 78 and 77', 78'. Contacts 77, 77' are connected by wires 80, 80' to the track rail section 7 aforesaid. Contacts 78, 78' are connected to wires 69, 69' leading to 100 one side of batteries 68, 68' so that on closure of armature 76 on said contacts 77, 78, etc., the batteries 68, 68' are put in connection with track rail section 7. From wire 67 connected to battery 68, a wire 82 leads to a relay magnet 83, whence a wire 84 leads to track rail section 8. Similarly a wire 67' connected to battery 68' leads to a relay magnet 83', whence a wire 84' leads to track rail section 8'. The armatures 86, 86' of the respective relays 83, 83' co-operate with front contacts 87, 87' normally open circuited, said armatures being connected respectively by wires 88, 88' to one side of main gate operating battery 89, and the said front contacts 115 for said armatures being connected by wires 90 and 90' respectively to the contacts 36 and 36' of the switch board 3. A hand switch 92 is interposed in the wire 90' aforesaid but as said switch is closed at all times during 120 the operation of the apparatus it will be disregarded in tracing the circuits. From the fixed contacts 35, 35' of the switch board wires 93, 93' lead respectively to the contacts 24, 24' of the main switch 6. From the contacts 25, 25', of said switch, wires 95, 95' lead respectively to solenoids 11, 12 both connected by wires 96 and 96' to a wire 97 connected to contacts 26, 26' of the switch board, a wire 98 leading from said contact to 130

The solenoid 44 for operating the armature switch 4 is connected at one side by wire 105 to the contact 27' of the main switch and at the other side by wire 106 to the common 20 return wire 102 aforesaid. A wire 129 leads from wire 98 to contacts 42' and 41' of the switch 4. Contacts 42 and 41 of said switch are connected respectively by wires 130 and 131 to opposite sides of the armature of the 25 motor 10. Wire 131 is connected by wire 132 to one of the contacts 52' for switch 50, the other contact 52 being connected by wire 133 to battery return wire 102. Wire 130 is connected by wire 132' to one of the contacts 30 51' for switch 50, the other contact 51' being connected by wire 133' to return wire 102.

established as follows: from battery 68 through wire 69, contact 78, armature 76, contact 77, wire 80 to track rail section 7 through car wheels to track rail section 8, thence through wire 84, magnet 83, wire 82 and wire 67 back to the other side of the battery 68. The armature 86 of the relay 83 then closes connection at contact 87 establishing a main battery circuit as follows: from battery 89 through wire 88, armature 86, contact 87, wire 90 to contact 36 on the switch board, thence through switch board 34, contact 35, wire 93', contact 24', switch contact 23, contact 25', wire 95', solenoid 12 and wire 96 to wire 97 leading to contacts 26 and 26' through wire 98 to field magnet of the motor 10 and from said field 95

wire 102. The reversing sections 8^a and 8^b of the track are provided with relays 108 and 108', connected by wires 109, 109' to sections 8^a and 8^b and by wires 110 and 110' to the continuous rail section 7. The armatures 111 and 111' of these relays are connected by wires 112 and 112' to said track rail 7 and the back contacts 113 and 113' of said relays are connected by wires 114 and 114' to relays 116 and 116' whose other sides are connected by wires 117 and 117' to the wire 82 aforesaid. Armature of relays 116 and 116' operate to close circuit connections 118 and 119, 118' and 119', between wires 88 and 90, and 88' and 90', similarly to the action of armatures 86 and 86'. 35 40 45 50 55 60 65 70 75 80 85 90 95 100 105 110

magnet through wire 101 and wire 102 back to the other side of the battery 89. The solenoid 12 being energized, moves the connection between main switch 6 so as to close the contacts 26 and 27 by means of contact 22 and also moves bar 15 so as to bring switch 120 into contact with fixed contacts 121 and 122. At this time current will flow from battery 89 to contact 26 as above described, thence through contact 22, contact 27, wire 126, wire 105, solenoids 44, and wire 106 to the return wire 102 leading to the other side of the battery 89. Solenoid 44 then draws up the armature switch 4, making a circuit for the armature of the motor 10 as follows: from battery 89 to wire 98 as described, then through wire 103, 104, 105, 106, 107, 108, 109, 109', 110, 110', 111, 111', 112, 112', 113, 113', 114, 114', 115, 115', 116, 116', 117, 117', 118, 118', 119, 119', 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 670, 671, 672, 673, 674, 675, 676, 677, 678, 679, 680, 681, 682, 683, 684, 685, 686, 687, 688, 689, 690, 691, 692, 693, 694, 695, 696, 697, 698, 699, 700, 701, 702, 703, 704, 705, 706, 707, 708, 709, 710, 711, 712, 713, 714, 715, 716, 717, 718, 719, 720, 721, 722, 723, 724, 725, 726, 727, 728, 729, 730, 731, 732, 733, 734, 735, 736, 737, 738, 739, 740, 741, 742, 743, 744, 745, 746, 747, 748, 749, 750, 751, 752, 753, 754, 755, 756, 757, 758, 759, 750, 751, 752, 753, 754, 755, 756, 757, 758, 759, 760, 761, 762, 763, 764, 765, 766, 767, 768, 769, 770, 771, 772, 773, 774, 775, 776, 777, 778, 779, 770, 771, 772, 773, 774, 775, 776, 777, 778, 779, 780, 781, 782, 783, 784, 785, 786, 787, 788, 789, 780, 781, 782, 783, 784, 785, 786, 787, 788, 789, 790, 791, 792, 793, 794, 795, 796, 797, 798, 799, 790, 791, 792, 793, 794, 795, 796, 797, 798, 799, 800, 801, 802, 803, 804, 805, 806, 807, 808, 809, 800, 801, 802, 803, 804, 805, 1467, 1468, 1469, 1470, 1471, 1472, 1473, 1474, 1475, 1476, 1477, 1478, 1479, 1470, 1471, 1472, 1473, 1474, 1475, 1476, 1477, 1478, 1479, 1480, 1481, 1482, 1483, 1484, 1485, 1486, 1487, 1488, 1489, 1480, 1481, 1482, 1483, 1484, 1485, 1486, 1487, 1488, 1489, 1490, 1491, 1492, 1493, 1494, 1495, 1496, 1497, 1498, 1499, 1490, 1491, 1492, 1493, 1494, 1495, 1496, 1497, 1498, 1499, 1500, 1501, 1502, 1503, 1504, 1505, 1506, 1507, 1508, 1

The operation is as follows: Normally the track switches 58 and 58' are open and the magnetic break switches 12 and 12' and 12'' are closed so that the block B is adapted to operate on closed circuit to control the block signal relay 56 in the usual manner. When a train enters the section 8, for example, the first wheels that pass over the track switch 58 for that section operate to close said track switch, said track switch being closed causes the electromagnets for said track switch to retain the switch in closed position, thereby closing a circuit from battery 68 through wire 70, wire 70^a, trip switch 38, contact 39, wire 71, contact 39', trip switch 38', wire 72, magnet 54^b, wire 73, contact 59, switch 58, wire 61', wire 62, magnet 54, wire 63, mag-

as described, thence through wire 129, contact 42', switch 4, contact 42, wire 130 to the motor armature and thence through wire 131, wire 132, gate controlled switch 50 and contacts 52' to wire 133 leading to battery return wire 102. The motor then operates to lower the gate, this operation being continued until the switch 50 is moved from contacts 52' and on to contacts 51', the operation of the motor then being stopped by breaking its energized connection at 52'. As the train begins to pass onto section 8' it closes connection between the track rail sections 8' and 7 and as the armature 76 is still closed on contact 77 and 77', 78 and 78', current will flow from battery 68' through wire 69', contact 78', armature 76, contact 77', wire 80' to track rail section 7, thence 130

- through car wheels to rail section 8' through wire 84', magnet 83', wire 82' and wire 67' back to the other side of the battery 68'. The armature 86' of the relay magnet 83' then closes connection at contact 87' establishing a circuit as follows: from battery 89 through wire 88', armature 86', contact 87', wires 90' and 93', switch 92, wire 90', wire 136 to solenoid 32', thence through wire 135, contact 122, switch 120, contact 121 and wire 137 to the battery return wire 102. Solenoid 32' then draws down the switch member 34' breaking the circuit at contacts 35' and 36' and locking the bar 15 by engagement of the core 31' with the shoulder 30 on said bar. When the last wheels of the train pass off of section 8, relay 83 is deenergized and circuit of solenoid 12 is thereby broken and the main switch returns to normal position, the switch 120 being held closed by locking means 31' and 30. The operating connection for solenoid 44 is broken as member 22 of switch 6 leaves contacts 26 and 27 and the switch 4 then falls into position to close connection between contacts 41 and 41' and current will then pass from battery 89 through wire 88, contacts 20, 19 and 21 to wire 97, contact 26' thence through wire 98, wire 129, contact 41', switch 4, contact 41, wire 131, armature of motor 10, wire 130, wire 132', contacts 51' and switch 50, wire 133' to battery return wire 102. The motor 10 will then operate the gate to raise the same until the gate-operating switch 50 is moved to position to open contacts 51' and to close contacts 52. Finally when the train has passed off section 8', relay 83' is also deenergized by the opening of its circuit at the track thereby breaking the circuit of the locking magnet 32' which allows core 31' to be raised by its spring so as to raise switch 34' and at the same time to disengage member 31' from shoulder 30. This allows the switch 120 to return to normal position. As the switch 34' returns to normal position it trips switch 38' and breaks the circuit of magnetic break switch solenoids 54, 54^a and 54^b and magnet 65, thereby restoring all the parts to normal position and putting the block B on closed circuit again.
- The function of switch 34' is to open the circuit of solenoid 11 as soon as the train passes from section 8 to section 8', thereby preventing the main switch from being operated in the reverse direction under these conditions. Similarly switch 34 operates to disable operating circuit for solenoid 12 when the train passes from section 8' onto section 8.
- When a train enters from the left it operates the switch 58' to close the energizing circuit for the magnets 54^b, 54^c, etc., and the operation proceeds in similar manner to that above described, to first lower the gate and then to raise it as the train passes onto the

section 8, the main switch 6 being in this case operated by solenoid 11, and operating to close switch 120. The magnets 108 and 108' for sections 8^a and 8^b are normally energized from the block signal battery 55 so that their armatures 111 and 111' are held out of contact with contacts 113 and 113' respectively. When a train entering from the left passes over section 8^b it temporarily deenergizes magnet 108' but as soon as the train has passed fully onto section 8' magnet 108' is energized and opens contact at 113.

If the train after passing onto section 8' and operating the gate mechanism as above described, to lower the gate, then backs off of section 8' without passing onto section 8, the wheels of the train will connect rail sections 8^b and 7, short-circuiting magnet 108' and causing the armature 111' of said magnet to drop, closing contact at 113'. Current then passes from battery 68' through wire 69', contact 78', armature 76, contact 77', wire 80', track section 7, wire 112', armature 111', contact 113', wire 114', magnet 116, and wires 117' and 67 back to the other side of battery 68'. Magnet 116' then raises its armature 119' closing contact at 118' and current then flows from battery 89 through wire 88' to armature 119' thence through contact 118' to wire 90' leading to contact 36', for switch 34'. From wire 90' current passes through wire 135 to solenoid 32', contacts 122, 120, 121 and wires 137 and 102 back to battery 89. Solenoid 32' then opens switch 34' and thereby opens the circuit for energizing solenoid 11 for main switch 6, and allows said switch to move to normal position, switch 120 being retained in closed position by core 31 of solenoid 32. Movement of switch 6 to normal position breaks the energizing circuit for solenoid 44, at contact 27' and the motor 10 is then operated to raise the gate in the manner above described. When the train backs wholly off of section 8^b, relay 119 is deenergized and the solenoid 32' is consequently also deenergized, with the result that switch 34' returns to normal position, opening the trip switch 38' momentarily and breaking the circuit of magnets 54^a, 54^b, etc., so as to return all parts to normal position.

In applying the invention to a double track railway the gate apparatus may be made in duplicate cross connection units as shown in my patent above referred to.

What I claim is:

1. A crossing gate apparatus adapted for operation with a track having a block signal, said apparatus comprising a gate, an electric motor for operating the same, and means for controlling said motor comprising insulated track sections adjacent the crossing, switch means for controlling said motor and a circuit including a source of

current and said insulated track sections and also including means for operating said motor switch means on closure of said circuit by a train, magnetic break means for 5 normally connecting said insulated track sections to close the track circuit for the block signal, and train-operated means for opening said magnetic break means when a train passes onto one of the insulated sections 10 at the crossing.

2. A crossing gate apparatus adapted for operation with a track having a block signal, said apparatus comprising a gate, an electric motor for operating the same, and 15 means for controlling said motor comprising insulated track sections adjacent the crossing, switch means for controlling said motor and a circuit including a source of current and said insulated track sections 20 and also including means for operating said motor switch means on closure of said circuit by a train, magnetic break means for normally connecting said insulated track sections to close the track circuit for the 25 block signal, and train operated means for opening said magnetic break means when a train passes onto one of the insulated sections at the crossing, said train operated means comprising a controlling circuit for 30 said magnetic break means and train operated switches in said circuit.

3. A crossing gate apparatus adapted for operation with a track having a block signal, said apparatus comprising a gate, an 35 electric motor for operating the same, switch means for controlling said motor, insulated track sections adjacent the crossing, a circuit including a source of current and said insulated track sections and also including 40 means for operating said motor switch means on closure of said circuit by a train, train-controlled means for normally connecting said insulated track sections to close the track circuit for the block system and 45 for breaking connection between said sections when a train is on one of the sections.

4. A crossing gate apparatus adapted for operation with a track having a block signal, said apparatus comprising a gate, said track being provided with insulated sections 50 on opposite sides of the crossing, electric controlling means and a motor operated thereby for operating said gate, said electric controlling means comprising a circuit including said insulated track sections and 55 switch operating means for said circuit to close the gate when a train passes onto an insulated track section in advance of the gate and to open the gate when the train passes onto the insulated track section beyond the gate, and means operated by said 60 motor controlling means on completion of operation of the gate to open the controlling circuit which maintains the insulated track sections in disconnected condition so as to 65 restore the track sections to closed circuit condition for control of the block signal.

5. In combination with a railway track provided with insulated track sections, a crossing gate located between said sections, 70 an electric motor for operating said gate, electric controlling means for said motor, and a controlling circuit including said controlling means and said insulated track sections for controlling said motor to close 75 said gate when a train passes onto the section in advance of the crossing and to open the gate when the train passes onto the section beyond the crossing, an insulated reversing track section beyond the aforesaid 80 track section at either side of the crossing, and electric controlling means connected to said reversing track sections to control the gate operating motor to open the gate.

In testimony whereof I have hereunto set 85 my hand at Hoopeston, Illinois, this 16th day of December, 1914.

JAY BRIGGS.
